TAKE-UP FOR LOOMS

George Crompton, Jr., Worcester, Mass.

Application July 31, 1941, Serial No. 404,753

7 Claims. (Cl. 139—304)

The invention relates to looms for weaving and knitting simultaneously and involves an improvement in the loom of my prior Patent No. 1,980,666.

One object of the invention is to keep the 5 knitted sections taut and prevent dropping of stitches. Another object of the invention is to speed the production of ribbon jersey on a loom of the type disclosed in my Patent No. 1,980,666. Another object of the invention is to improve the 10 functioning of a loom constructed according to the said patent. Another object of the invention is to provide a take-up for the knitted portions of ribbon jersey without interfering with the functioning of the loom in other respects. Another object of the invention is to provide two 15 take-ups for looms of the class indicated, one for the knitted part of the fabric and the other for the woven part. Other objects will be in part obvious or in part pointed out hereinafter.

The invention accordingly consists in the features of construction, combinations of elements, arrangements of parts and in the several steps and relation and order of each of said steps to one or more of the others thereof, all as will be 20 illustratively described herein, and the scope of the application of which will be pointed out in the following claims.

In the accompanying drawings illustrating one of many possible embodiments of the mechanical features of this invention

Figure 1 is a side elevation of the front of a loom according to Patent No. 1,980,666 illustrating the drive for the two take-up motions;

Figure 2 is a front elevation of the knitting take-up drive and a portion of the take-up rolls;

Figure 3 is a side elevation showing the details of the drive for the knitting take-up on a somewhat enlarged scale as compared with Figure 1;

Figure 4 is a front elevation of the knitting take-up rolls and controlling mechanism;

Figure 5 is a plan view of the same;

Figure 6 is a detail of the knitting take-up pawl, bell crank lever and ratchet.

As conducive to a clearer understanding of the present invention it may be noted that a loom constructed strictly in accordance with my Patent No. 1,980,666 operates properly, but the lack of a firm tension on the knitted sections is noticeable. Due to the fact that the woven sections of the 45 fabric can be stretched only to a limited degree there is a slack in the knitted sections regardless of how the fabric take-up is adjusted that causes an irregular and loose stitch, occasionally resulting in holes in the knitting and generally 50

slowing down production. I have found that it is possible to apply a separate take-up to the knitted portions of the goods which, however, does not interfere with the cloth take-up and tensions only the knitted sections right adjacent to the needles, which results in correcting the condition mentioned and achieves the objects hereinbefore set forth.

Referring now to Figure 1, the right-hand 10 loom side of a loom according to Patent No. 1,980,666 is indicated at 10. The knitting cam shaft of the loom is indicated at 11. On this cam shaft 11 is a take-up cam 12. This cam happens to have four lobes because I have found that a practical ratio of weaving to knitting is four to one, that is to say, four picks are inserted in the goods to every course that is knitted. The knitting cam shaft 11 controls the knitting and one course is knitted for every revolution thereof, 15 while it is customary, as is known, to actuate the cloth take-up once for every pick of the loom.

The take-up cam contacts a roller 13 on one 20 end of a bell crank lever 14 pivoted at 15 to the loom side 10. A turnbuckle 16 has a stud 17 which is connected to the bell crank lever 14 in a desired position of adjustment in a slot 18. The turnbuckle 16 has screwed thereinto a link rod 19 which is screwed into a turnbuckle 20 from 25 which projects a stud 21 in a desired position of adjustment in a slot 22 of a pawl lever 23 pivoted on a stud shaft 24 projecting from a take-up bracket 25 which is fastened at the top to the breast beam 26 and at the bottom to a cross shaft 27 extending between projections 28 of the loom 30 sides 10. The breast beam 26 is fastened to the upper front part of the loom side 10 and the corresponding part of the opposite loom side (not shown).

A take-up pawl 30 is pivotally mounted on the upper end of the pawl lever 23 and engages a ratchet wheel 31 to which is fastened a pinion gear 32 meshing with a large gear 33 to which is fastened a pinion gear 34 on a stud 35 extending from the bracket 25. The pinion 34 meshes with a large gear 36 which is fastened to the shaft 37 of a sand take-up roll 38. A hold pawl 39 pivoted at 40 on an extension 41 of the bracket 25 engages the ratchet wheel 31 and prevents retrograde movement of the take-up mechanism except when the hold pawl is lifted. Take-up ratchet wheels 31 with different numbers of teeth may be substituted and the gears may be changed to vary the number of picks to the inch in accordance with usual practice.

The cloth 45 goes over a breast roll 46 having

trunnions 47 resting in supports 48 extending upwardly from the breast beam 28. Thence the cloth goes downwardly around a roller 49 having trunnions 50 fitting in recesses 51 in the take-up brackets 25, thence around the sand take-up roll 38, thence over a roller 52 having trunnions 53 fitting in holes in forward projections 54 of the take-up brackets 25, thence over a roller 56 having trunnions 57 fitting in recesses in projections 58 of the brackets 25; thence to a cloth roll 60 where the cloth winds in the usual manner. The cloth roll 60 is driven in any usual way, not shown, to wind up the cloth as it is delivered regardless of the diameter of roll and cloth until it is full. A spring 61 fastened to the loom side 10 and to the stud 17 keeps the roller 13 in contact with the cam 12. The foregoing is a standard take-up for weaving looms and any variety thereof may be substituted so far as my invention is concerned.

To this or any other take-up I add a take-up which operates only on the knitted sections of the goods and which is located between the described take-up and the fell 62 of the goods. That is to say my additional take-up operates between the sand roll 38 or its equivalent and the fell of the goods and only upon the knitted portions which can be stretched, whereas the woven sections cannot be stretched to any considerable extent. Referring now to Figure 4, I provide an upper roll 70 and a lower roll 71. These rolls are desirably made of wood and have trunnions 72 and 73 at their opposite ends. I cut soft tubular rubber into sections 75 and force them onto the trunnions 72 and 73 so that they are spaced adjacent each other on the rolls 70 and 71 which are parallel in the loom. These sections 75 are of a length and so spaced that they will contact the knitted sections of the fabric but allow the woven sections thereof to pass through spaces 76 between the sections 75. I have found that in order to grip all the knitted sections with an even tension it is desirable to mount the rolls 70 and 71 on a grinder and to grind the sections 75 to uniform diameters and smooth surfaces.

Referring now to Figure 2, upstanding from the loom side 10 is an angle bracket 80. Referring to Figure 4, upstanding from the left-hand loom side (not shown) is a similar asymmetric angle bracket 81 only a fragment of which is shown. These brackets 80 and 81 have rectangular parallelipedal end portions 82 and 83.

Referring to Figures 2 and 4, supporting brackets 84 and 85 encompass the end portions 82 and 83 and are adjustably clamped thereto. Cup bearings 86 and 87 are bolted to the brackets 84 and 85 respectively. The trunnions 73 rest in these cup bearings 86 and 87 and thus the roll 71 is rotatably supported below the goods 45.

Since guides 88 and 89 encompass the brackets 84 and 85 respectively. They have journals 90 and 91 respectively for the trunnions 72. To the trunnions 72 are fastened ratchet wheels 93 and 94 at the right and left respectively. Referring now to Figures 4 and 6, a bell crank lever 95 is pivotally mounted on the right-hand trunnion 72. A pawl 96 is pivotally mounted on the bell crank lever 95 and engages the ratchet wheel 93. The other end of the bell crank lever 95 is a fork 97 in which, as best shown in Figure 5, fits the end of an arm 100. The arm 100 is fastened to the end of a shaft 101 extending through and journaled in the bracket 85. To the other

end of the shaft 101 is fastened an arm 102. Referring to Figures 1, 2, 3 and 5, the arm 102 has a slot 103 at its outer end in which fits a pin 104 extending through a forked piece 105 attached to the upper end of a rod 106. The rod 106 is slideable vertically in a bracket 107 attached to the loom side 10. At the bottom of the rod 106 is an abutment end piece 108. A spring 109 (Figure 2) tends to hold the rod 106 down, being connected to the arm 102 and the bracket 107. The abutment piece 108 is adjustable on the rod 107, being screw threaded thereon, and a nut 109 being provided for locking the parts in adjusted position.

Referring now to Figures 1 and 2, to the cam-shaft 11 outside the loom side 10 is fastened a cam 110. This cam 110 engages a roller 111 on a pin 112 in a fork 113 fastened to the lower end of a rod 114 mounted for vertical movement in a bracket 115 attached to the loom side 10. A spring 116 on the rod 114 between the bracket 115 and the fork 113 urges the rod 114 downwardly to keep the roller 111 in contact with the cam 110.

Referring now to the left-hand side of Figure 25 4, extending from the side guide 88 is a bracket 120 pivotally mounting a hold pawl 121 engaging the ratchet wheel 93.

The rubber sections 75 of the rolls 70 and 71 grip the knitted portion of the fabric. The cam 30 110 is so shaped that it raises the roll 111 gradually at a particular angular position in its revolution, and thereby raises the rod 114 which contacts the abutment 108 on the rod 106, thus raising the pin 104 which moves the arm 102 upwardly, rocking the shaft 101 and depressing the arm 100 the end of which extends into the fork 97 on the end of the bell crank lever 95, thus rocking the bell crank lever 95 and moving the pawl 96 which engages and moves the ratchet wheel 40 93. Since the ratchet wheel 93 is fastened to a trunnion 72 of the upper roll 70, the upper roll 70 is angularly moved (and in a direction to tension the knitted sections of the fabric). The mechanism is preferably timed so that this take-up 45 pulse is imparted just as the needles (not shown) of the knitting mechanism go rearwardly through the knockover bits (not shown). Reference may be made to my prior patent for disclosure of the 50 needles (which are standard spring beard needles) and of the knockover bits (which are substantially conventional in shape).

It is at that precise point in the knitting cycle that tension is most needed upon the knitted portion of the fabric. When the needles move 55 rearwardly between the knockover bits, the old course is being cleared. If it is not cleared, in any particular wale, a defect is apt to occur. By taking up the knitted portions of the fabric at this moment in the knitting cycle, complete 60 knocking over is assured.

The hold pawl 121 acting on the ratchet wheel 84 holds the upper roll 70 from retrograde movement. The amount of the take-up can be adjusted by selecting different ratchet wheels 93 65 and 94 and/or by varying the stroke of the pawl 96. It is wise to make the knitting take-up move the knitted portions of the fabric 45 at a slightly faster rate (say ten per cent) than the sand roll 38 takes up the entire goods, because thereby the 70 knitting take-up will always be ahead of the fabric take-up, but the knitted sections will not be torn, since the contact of the rubber sections 75 is a resilient yielding contact.

The roll 70 and its rubber sections 75 rests 75 upon the roll 71 and its rubber sections 75, with

the knitted fabric in between them. The weight of the slide guides 88 and 89 adds to the weight of the roll 70. The lower roll 71 has a tendency to sag in the middle, but so also does the upper roll 70 and as a practical matter contact of each pair of tubular rubber sections 75 is found to occur. Compensating weighting of the upper roll 70 by lead plugs inserted into the wood or by lead rings wrapped around the roll 70 between the sections 75 (still of not sufficient thickness to contact the woven portions) may be resorted to in particular cases where some intermediate knitted section is found to be slipping too much.

The special knitting take-up of this invention in no wise interferes with the regular take-up, as herein described, which determines the number of picks per inch inserted in the woven parts of the goods. Furthermore, it also does not change the number of courses per inch, which is a mathematical function of the picks per inch represented by a small whole number exactly equal to the ratio of the R. P. M. of the back shaft (not shown) which controls the weaving, to the R. P. M. of the knitting camshaft which controls the knitting. The special knitting take-up simply provides tension on the knitted portions at the proper time without interfering with the functioning of the loom. Although it is preferred to take-up suddenly as the needles move rearwardly between the knockover bits, some results can be achieved regardless of the moment when the pawl 96 moves and how fast, since a generally maintained tension on the knitted sections will improve the action of the looms.

It is noted that the special mechanism of this invention operates automatically and requires no attention in operation. Nevertheless the construction of the mechanism is such that the top roll 70 can very quickly be lifted and even removed altogether from the machine in case work such as "piecing on" is to be done, or when setting up the loom. Furthermore, at the start of operations, an initial tension can be put upon the knitted sections simply by pulling the knitted sections forwardly between the rolls 70 and 71.

While in the preferred form of my invention both take-ups operate intermittently, they might operate continuously at a constant and predetermined rate. It is simpler, however, to provide ratchet and pawl take-ups since much gearing that would otherwise be needed is dispensed with, and changes in the rate of take-up can be more easily made. Any type of friction roll capable of gripping the cloth with a firm grip can be substituted for the sand roll 88. This take-up roll positively moves the cloth. The sections 75 could be made of any material, but a cushioning material is preferred. The rolls 70 and 71 are yieldingly urged together to press the knitted portions between the sections 75 and they yieldingly grip the cloth or fabric.

It will thus be seen that there has been provided by this invention apparatus in which the various objects hereinabove set forth together with many thoroughly practical advantages are successfully achieved. As many possible embodiments may be made of the above invention and as many changes might be made in the embodi-

ment above set forth, it is to be understood that all matter hereinbefore set forth or shown in the accompanying drawings is to be interpreted as illustrative and not in a limiting sense.

5 I claim:

1. In a loom, take-up means capable of gripping the cloth with a firm grip, positive means to move said take-up means at a known average peripheral velocity, a pair of rolls one on either side of the cloth between the said take-up means and the fell cushioningly gripping the cloth with a resilient yielding contact, and means to drive one of said rolls at a known average peripheral velocity which is slightly in excess of the average peripheral velocity of the take-up means.
- 10 2. In a loom, a breast roll, a positively driven, positively gripping take-up below the breast roll actuated at a predetermined rate and adapted to tension a length of fabric, and a positively driven but yieldingly engaging take-up also actuated at a predetermined rate to tension portions of the said length of fabric and located between the breast roll and the fell of the goods.
- 15 3. A take-up for looms, particularly for the production of ribbon-jersey comprising a pair of rolls, means mounting the rolls one above the other on either side of the fabric, one at least of the rolls having sections, that is, having contacting portions of full diameter separated by portions of less diameter, positive means to rotate one of said rolls at a predetermined rate, and additional constant speed take-up means acting on the fabric beyond, i. e., farther from the fell than the said rolls.
- 20 4. In a take-up as claimed in claim 3, the combination with the parts and features therein specified, of cam means, and a pawl and ratchet to drive one of the rolls.
- 25 5. In a take-up as claimed in claim 3, the combination with the parts and features therein specified, of contacting sections formed out of cushioning material.
- 30 6. A take-up for looms comprising a first roll having trunnions, journals for the trunnions, slide guides for the journals, a ratchet wheel affixed to each trunnion, a second roll under the first roll and parallel to it, journals for the second roll, a pawl and actuating mechanism to drive one of the ratchet wheels, a hold pawl for the other ratchet wheel, one at least of said rolls having sections of greater diameter than the intervening portions of said roll, whereby to grip fabric at given portions only and tension it at such portions, and additional constant speed take-up means acting on the fabric beyond, i. e., farther from the fell than the said rolls.
- 35 7. A take-up for looms comprising a pair of rolls one of which has sections of a given diameter separated by portions of less diameter, means mounting one of said rolls in fixed position but permitting rotation, means mounting the other roll parallel to the first roll but free to approach and recede from it and also free to rotate, means to drive one of said rolls, and additional constant speed take-up means acting on the fabric beyond, i. e., farther from the fell than the said rolls.
- 40 8. A take-up for looms comprising a pair of rolls one of which has sections of a given diameter separated by portions of less diameter, means mounting one of said rolls in fixed position but permitting rotation, means mounting the other roll parallel to the first roll but free to approach and recede from it and also free to rotate, means to drive one of said rolls, and additional constant speed take-up means acting on the fabric beyond, i. e., farther from the fell than the said rolls.
- 45 9. A take-up for looms comprising a pair of rolls one of which has sections of a given diameter separated by portions of less diameter, means mounting one of said rolls in fixed position but permitting rotation, means mounting the other roll parallel to the first roll but free to approach and recede from it and also free to rotate, means to drive one of said rolls, and additional constant speed take-up means acting on the fabric beyond, i. e., farther from the fell than the said rolls.
- 50 10. A take-up for looms comprising a pair of rolls one of which has sections of a given diameter separated by portions of less diameter, means mounting one of said rolls in fixed position but permitting rotation, means mounting the other roll parallel to the first roll but free to approach and recede from it and also free to rotate, means to drive one of said rolls, and additional constant speed take-up means acting on the fabric beyond, i. e., farther from the fell than the said rolls.
- 55 11. A take-up for looms comprising a pair of rolls one of which has sections of a given diameter separated by portions of less diameter, means mounting one of said rolls in fixed position but permitting rotation, means mounting the other roll parallel to the first roll but free to approach and recede from it and also free to rotate, means to drive one of said rolls, and additional constant speed take-up means acting on the fabric beyond, i. e., farther from the fell than the said rolls.
- 60 12. A take-up for looms comprising a pair of rolls one of which has sections of a given diameter separated by portions of less diameter, means mounting one of said rolls in fixed position but permitting rotation, means mounting the other roll parallel to the first roll but free to approach and recede from it and also free to rotate, means to drive one of said rolls, and additional constant speed take-up means acting on the fabric beyond, i. e., farther from the fell than the said rolls.
- 65 13. A take-up for looms comprising a pair of rolls one of which has sections of a given diameter separated by portions of less diameter, means mounting one of said rolls in fixed position but permitting rotation, means mounting the other roll parallel to the first roll but free to approach and recede from it and also free to rotate, means to drive one of said rolls, and additional constant speed take-up means acting on the fabric beyond, i. e., farther from the fell than the said rolls.

GEORGE CROMPTON, JR.

Patent No. 2,343,135

Granted February 29, 1944

GEORGE CROMPTON, JR.

The above patent was extended September 4, 1951, under the provisions of the act of June 30, 1950, for 2 years and 254 days from the expiration of the original term thereof.

Commissioner of Patents.
